SIGN CARRIER

Earl C. Brownell, Portland, Oreg.

Application November 18, 1938, Serial No. 241,242

4 Claims. (Cl. 40—11)

This invention relates to sign carriers and is particularly adapted for holding signs to shelves and the like.

The primary object of the invention is to provide a clamp for holding a portable sign that consists of one piece of material.

Another object of the invention is to provide a clamp for grasping the sign that can be released from the sign by compressing the clip.

10 A still further object of the invention is to provide a clamp that will grip shelving and the like of different thickness with the same effective amount of grip without unduly distorting.

These and other incidental objects will be apparent in the drawing, specification and claims to follow.

Referring to the drawing:

Figure 1 is a perspective view of the clamp for holding portable signs and the like.

20 Figure 2 is a sectional view of a shelf, illustrating the clamping mechanism attached thereto.

Figure 3 is a perspective view of the lower end of the holding clamp, illustrating the clip for holding the sign.

25 Figure 4 is an edge view of the sign engaging clamp, the sign being shown in vertical section, the clamp being shown in sign engaging position in full lines and in sign releasing relation in dotted lines.

30 In the drawing:

1 is the main body portion of my new and improved holding clamp for supporting signs and the like to shelving. 2 indicates the usual conventional shelf, having my holding clamp clamped thereon. The upper end of the body 1 terminates in a flat circle 3, turned downwardly at 4 at a right angle. The turned portion 5 extending downwardly is again bent at right angles at 6, forming a horizontal portion 7, or this portion may be formed in the shape of a circle. An

40 upwardly extending portion 8 terminates in a loop 9 for the purpose of bearing on the under surface 10 of the shelf. The circular portion 3 rests on the top of the shelf, as shown in Figure 45 2. The downwardly extending portion 5 extends down over the front of the shelf. The portion 7 extends rearwardly terminating in the upwardly extending arm 8 under the center of the loop 3, this causes a clamping action against the shelf 2.

50 One of the primary objects of this invention, as far as the clamp just described, is that a spring tension is maintained completely through the loop 3, the downward portion 5, the portion 7 and the terminating clamp portion 8, which makes it

almost impossible to spring the clamp out of shape, at the same time giving an effective gripping action regardless of the thickness of the shelving; if there were any short twisted bends or the like this would not be possible and herein resides a very important feature. 5

Referring to the lower portion of the holding arm 1, a loop 11 is formed, a reverse bend is made at 12, extending downward forming the loop 13, which has another reverse bend 14, finally terminating in the extension 15. 10

Referring to Figure 3, the loop 11 is shown bearing against the surface 16 of the sign 17, the loop 13 bears against the opposite side of the sign 17, 15 gripping the sign therebetween.

Referring to Figure 1, it will be noted that the loop 13 extends forwardly of the loop 11, but when the sign 17 is inserted the loop 13 is forced backward of the loop 11 sufficient distant by pressure on the arm 15 to permit the sign 17 being 20 inserted between the loop 11 and the loop 13, best shown in Figures 3 and 4.

The arm 15 is for the purpose of forcing the loop 13 in between and behind the loop 11 when pressure is brought to bear on the arm 15, allowing 25 the insertion of the sign 17 or the removal thereof of the sign.

It will therefore be readily understood that I have provided a holding bracket for supporting portable signs constructed of one piece of material providing for a means of clamping it to a support and a simple gripping means for holding the sign or card on its opposite end. 30

I do not wish to be limited to the exact shape and construction, as other modifications could be 35 made, still coming within the scope of the claims to follow.

What is claimed to be new is:

1. A portable sign carrier for shelves and the like, comprising an appropriate length of wire-like element formed at one end with a shelf engaging clamp and at the opposite end with a sign engaging clamp, the sign engaging clamp comprising integral relatively outer and inner loops between which the sign is inserted, the inner loop extending normally at an angle to the outer loop with the free end of the inner loop 40 forward of the plane of the outer loop to provide a clamping action when the loops are separated by an inserted card, and means carried by 45 the inner loop whereby such inner loop may be moved into a plane outwardly from that of the outer loop to release an inserted card at will. 50

2. A portable sign carrier for shelves and the like, comprising an appropriate length of wire- 55

- like material, a shelf engaging clamp at one end thereof and a sign engaging clamp at the other end thereof, the sign engaging clamp being formed integrally with the element by bending the element into U-form to provide an outer loop and projecting the element beyond the loop form to provide a U-shaped inner loop of less transverse and vertical dimensions than those of the outer loop, the normal plane of the inner loop being at an angle to the plane of the outer loop, the element beyond the inner loop being extended in the form of an arm at an angle to the inner loop to provide a means whereby the inner loop may be manually moved into a plane beyond that of the outer loop.
3. A portable sign carrier for use with shelves and the like, comprising an appropriate length of wire-like element formed at one end with a shelf

clamp including a flat circular formation having a depending portion normally at right angles to the plane of the circular formation, a lateral extension normally at right angles to the plane of the depending portion, and an upwardly extending arm normally parallel to the depending portion with a curved terminal, the opposite end of the wire-like element having a sign engaging clamp.

4. A construction as defined in claim 3, wherein the shelf engaging clamp and sign engaging clamp are normally in relatively right angularly related planes to permit a sign inserted in the sign engaging clamp to depend vertically in readable position while the shelf engaging clamp operates with a horizontally disposed shelf.

EARL C. BROWNELL.
